UNITED STATES PATENT OFFICE.

THEODORE P. BROWN, OF WORCESTER, MASSACHUSETTS, ASSIGNOR TO EARLE E. CONWAY, OF BOSTON, MASSACHUSETTS, CARLE C. CONWAY, OF NEW YORK, N. Y., AND SAID THEODORE P. BROWN, OF WORCESTER, MASSACHUSETTS, TRUSTEES DOING BUSINESS AS SIMPLEX PLAYER ACTION COMPANY.

MOUNTING FOR ELECTRIC MOTORS.

Application filed November 7, 1921. Serial No. 513,621.

To all whom it may concern:

Be it known that I, THEODORE P. BROWN, a citizen of the United States, residing at Worcester, in the county of Worcester and Commonwealth of Massachusetts, have invented a new and useful Improvement in a Mounting for Electric Motors, of which the following, together with the accompanying drawings, is a specification.

10 My invention relates to an improved mounting for electric motors, such as are employed to drive the operating mechanism of player pianos and other similar mechanically driven musical instruments.

15 The object of my invention is to provide an improved mounting for an electric motor so arranged that substantially no vibrations, due to the operation of the motor, will be transmitted from the motor to the member upon which the motor is supported, such, for example, as the base board of a piano. Obviously, the transmission of any such vibrations to the piano frame would be extremely undesirable, for they tend to set up noises which would be audible while the piano is being played.

20 By my invention, I provide a mounting for a motor, so constructed that no vibrations will be transmitted from the frame of the motor. Other advantageous features of my invention will hereinafter appear, reference being had to the accompanying drawings, in which—

25 Fig. 1 is a view in end elevation of an electric motor mounted in accordance with my invention.

Fig. 2 is a view in side elevation of the parts shown in Fig. 1.

30 Fig. 3 is a plan view of the mounting with the motor removed therefrom to illustrate the parts more clearly.

Like reference characters refer to like parts in the different figures.

35 Referring to the drawings, a motor generally indicated at 1 is provided with a driving shaft 2 having a pulley 3 mounted thereon, from which power is transmitted to a pulley 4 by means of a belt 5. The pulley 4 is mounted on a shaft 6 which is connected to the operating mechanism of a player piano action. Inasmuch as the particular type of piano player action forms

no part of the present invention, it will not be further described herein.

The frame of the motor 1 is provided with 55 feet 7 located at its corners, and the pair of feet 7 on the same side of the motor 1 are secured to a flexible member 8 by means of bolts 9 and nuts 10 cooperating therewith. Each member 8 is preferably formed of 60 some suitable flexible durable material, such as the closely woven fabric often employed for straps or belting. The respective ends of each member 8 are looped over rods 11, the free ends being secured to the remainder 65 thereof by means of the bolts 9, so that the strap 8 is stretched tightly between the rods 11 and at the same time is capable of turning slightly at its looped ends on the rods 11. 70

The rods 11 are supported at their ends between blocks 12 extending substantially at right angles to the rods 11. The blocks 12 are provided with openings 13 for receiving bushings 14 which surround the end 75 portions of the rods 11. Each bushing 14 is formed of some relatively soft shock absorbent material, such as felt, which, being of a frictional nature, permits the rods 11 to move therein without sliding freely. The 80 blocks 12 are supported upon the base 15 of the instrument by means of strips 16 of some soft compact material, such as felt, the blocks 12 being secured to the base 15 by any suitable means. 85

A spring 17 is secured at its ends between one bearing 18 of the motor 1 and a side wall 19 of the piano casing. The spring 17 tends to hold the shaft 2 away from the shaft 6 and thereby keep the belt 5 tight, it being 90 obvious that the entire motor is capable of lateral horizontal movement with respect to the shaft 6, by reason of the fact that the rods 11 may slide in the bushings 14.

From the foregoing, it is apparent that I 95 have provided an improved motor mounting, so constructed that when the motor is running, substantially no vibrations can be transmitted to the base upon which the motor is supported. It is obvious that any vibrations of the motor 1 will be absorbed, first, by the flexible straps 8, upon which the motor frame is directly mounted, and then by the bushings 14 which support the 100

rods 11 and also allow slight movement of the motor by the spring 17 in order to keep the belt 5 tight. Finally, any very slight vibrations which may possibly reach the blocks 12 will be absorbed by the strips 16 which support the blocks above the base member 15. Consequently, the motor 1 may be operated to drive the player action of the piano without setting up any noises which 10 might prove disturbing while music is being played by the instrument.

While I have shown my improved motor running in its simplest and preferred form, it is not so limited but is susceptible of various modifications within the scope of the 15 appended claim.

I claim,

A mounting for motors, comprising a pair of spaced horizontal members substantially parallel, a pair of rods extending between 20 and through said horizontal members, said rods being also horizontal and substantially perpendicular to said members, shock absorbent bushings to slidingly receive the rods in the members, a pair of straps looped 25 around said rods, drawn taut between the rods, and fastened to a motor frame to hold the motor resiliently, with the motor shaft substantially parallel to the said horizontal members.

Dated this 31st day of October, 1921.

THEODORE P. BROWN.
